UNITED STATES PATENT OFFICE

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA

GRADUATED SEMIELLIPTIC SPRING

Application filed March 20, 1930. Serial No. 437,502.

This invention relates to car trucks, and more particularly to the car trucks of street railway cars.

An important object of the invention is the provision in a car truck construction of spring means connecting the bolster and truck frame of such character and so connected with the frame and the axles that a greater bearing of the journal box on the axle is obtained.

A still further object of the invention is the provision of a structure of this character embodying primary and auxiliary springs at each side of the truck, these springs being so arranged that the auxiliary spring carries no load during ordinary loading of the car and only comes into play when the car is loaded to a point approaching its maximum capacity.

20 A still further object of the invention is the provision of a structure preventing the troubles ordinarily occurring when the normal load-supporting spring breaks.

These and other objects I attain by the construction shown in the accompanying drawings wherein, for the purpose of illustration, I have shown a preferred embodiment of my invention and wherein:

Fig. 1 is a fragmentary plan view of a truck embodying my invention;

Fig. 2 is a side elevation thereof; and

Fig. 3 is a sectional view illustrating the spring mounting on the bolster.

Referring now more particularly to the drawings, the numeral 10 generally designates a truck bolster; 11, wheel axles; and 12, the journal boxes thereof. The journal boxes are made wider than in the ordinary construction and are provided with a flat upper surface 13. Adjacent each side thereof the bolster 10 is provided with a horizontally-extending flat surface 14 providing a seat for a pair of inverted semi-elliptic springs 15 and 16 hereinafter referred to as main and auxiliary springs. These springs, as in the usual construction, are centrally banded at 17 and the surface 14 is recessed as at 18 to receive these bands.

A spring yoke 19 is provided for each pair of springs 15-16, this yoke being bolted at

its inner end to the bolster as at 20, extending upwardly and over the spring 16 in spaced relation thereto and is then provided with a downwardly offset portion 21 abutting against the upper surface of the spring 15 to clamp the same against the bolster. This end of the yoke is secured by bolts 22, and other bolts 23 preferably connect the yoke adjacent the offset with the bolster, these latter bolts passing between springs 15 and 16. The outer ends of springs 15 and 16 seat upon the journal boxes 12 between outer faces 13 thereof, and are held thereagainst by a superimposed plate 24, bolted to the journal box by bolts 25 serving to maintain the proper spaced relation of the ends of springs 15 and 16 and to hold these springs in proper alignment. It will be obvious that the use of the pair of springs provides a wider seating surface so that a greater bearing of the journal box upon the axle is provided and the tendency to proper alignment is promoted. When spring 15 has been sufficiently compressed, the spring 16 will engage against the under surface of the portion 19 of the yoke and compression of this spring will begin, spring 16 from this point on complementing spring 15 in its action.

Since the specific arrangement hereinbefore set forth is obviously capable of a considerable range of change and modification without in any manner departing from the spirit of my invention, I do not wish to be understood as limiting myself thereto except as hereinafter claimed.

I claim:

1. In a car truck, spaced axles and an intermediate bolster, the axles having aligned journal boxes providing relatively wide seats upon their upper surfaces, a pair of leaf springs arranged in side to side relation secured at their ends to said journal boxes and at their centers operatively engaging said bolster, one of said springs being rigidly fixed to said bolster and means carried by the bolster and co-acting with the other spring to engage and flex the said other spring when the bolster has been depressed to a predetermined extent against the action of the first-named spring.

2. A truck comprising parallel axles having relatively wide faced journal boxes at opposite ends thereof and a pair of parallel leaf springs disposed at each side of the truck and having their ends rigidly secured to the said journal boxes.
3. A truck comprising parallel axles having relatively wide faced journal boxes at opposite ends thereof, a pair of parallel leaf springs disposed at each side of the truck and having their ends rigidly secured to the said journal boxes, a bolster extending transversely of the truck at the approximate center thereof, and means on said bolster engaging the upper surface of one of said springs and vertically-spaced from the upper surface of the other of said springs.
4. A truck comprising parallel axles having relatively wide faced journal boxes at opposite ends thereof, a pair of parallel leaf springs disposed at each side of the truck and having their ends rigidly secured to the said journal boxes, and a bolster extending transversely of the truck at the approximate center thereof, including a member having a portion directly engaging the upper surface of one of said springs and a second portion vertically offset with relation to the first-named portion and extending over the other of said springs in spaced relation thereto.
5. In a car truck, spaced axles, an intermediately disposed bolster and a pair of springs connecting the axles adjacent each end thereof and supported thereby, one of said springs at each side of the truck supporting the bolster under normal loads, the other of said springs assisting to support the bolster under abnormal loads and supporting the bolster in event of breakage of the first-named springs, said springs each comprising a leaf spring, the springs at each end of the axles being spaced longitudinally of the axle.
